UNITED STATES PATENT OFFICE.

RAY E. DE CAMP, OF WILKINSBURG, PENNSYLVANIA, ASSIGNOR TO WESTINGHOUSE ELECTRIC & MANUFACTURING COMPANY, A CORPORATION OF PENNSYLVANIA.

CURRENT-LIMIT RELAY.

1,392,249.

Specification of Letters Patent. Patented Sept. 27, 1921.

Application filed June 21, 1918. Serial No. 241,259.

To all whom it may concern:

Be it known that I, RAY E. DE CAMP, a citizen of the United States, and a resident of Wilkinsburg, in the county of Allegheny 5 and State of Pennsylvania, have invented a new and useful Improvement in Current-Limit Relays, of which the following is a specification.

My invention relates to electromagnets and electromagnetically actuated switches for the control of electric circuits. In a more limited aspect, my invention relates to switches that are particularly adapted for unit-switch-control systems.

15 Control systems of the unit-switch type, largely used for governing electric motors, comprise a plurality of independently operated individual switches designed and connected to act successively to produce a 20 gradual acceleration of the motors with which they are associated. In these systems, devices are ordinarily employed for delaying the action of the successive switches in order to avoid injuring the motors by excessive currents. One form of these devices 25 comprises a plurality of auxiliary switches or relays mechanically interlocked with the main switches, so that it is impossible to close any main switch before the closing of 30 the preceding switch of the series. It is found in practice, nevertheless, that, though each switch closes before the corresponding 35 relay can cause the closing of the next succeeding switch, there is usually not a sufficient time interval between the closing of two successive switches to prevent excessive current peaks.

To lengthen the time interval, the relays are, in some systems, provided with holding 40 coils energized by the motor current, which coils have a tendency to keep the relays open until the armature current reaches a predetermined safe value. Such systems, however, have not proved entirely satisfactory. 45 For one reason, the necessary mechanical interlock between the switch and the relay complicates the apparatus, adds to the expense, and increases the liability of failure of the apparatus to function properly. The 50 current, furthermore, does not always rise rapidly enough to so energize the holding coils as to prevent the relays from closing prematurely, and it thus happens that, as there is nothing to limit the operation of 55 these relays except the inherent time element

of the relays themselves, sections of the resistor are prematurely shunted, and the current is permitted to reach excessive values. Switches of the series-lockout type have also been employed but, as these operate within predetermined current limits only, it frequently happens, particularly on light loads, that the current drops too quickly through these limits to give the switches time to operate, and, as the current 60 continues to decrease beyond the lower limit, the switches fail altogether to close.

The purpose of my invention is to provide a current-limit accelerating relay which will avoid these defects. My relay is biased 70 toward closed position, but is maintained in open position until the motor current falls to the proper value. In one form of my invention, the peak value of the current is employed to compress a spring which, thereupon, allows the relay to close as soon as the current reaches a previously selected safe 75 value. The motor circuits may be so arranged, however, that the magnetism of the actuating coil of the relay shall perform the 80 function of the spring, this magnetism serving both to open the relay, in opposition to the biasing force, and to maintain the relay in open position until it is permitted to close by the conditions of the motor circuit. 85 In either case, the current itself is made to perform the work of releasing the relay at the proper time.

An object of my invention is to provide a novel device for operating the relays of a 90 motor-accelerating system.

Another object of my invention is to provide a single controlling means for these relays.

Other objects of my invention will be 95 made clear from the following description, when taken in connection with the accompanying drawings, in which Figure 1 is a side elevation, and Fig. 2 an end elevation of one form of my invention; Fig. 3 is a 100 detail of a modification; Figs. 4, 5 and 6 are, respectively, a side and an end elevation and a plan view of another modification; Fig. 7 is a detail of still another modification; Fig. 8 is a diagrammatic view of circuits and apparatus illustrating the operation of the modification shown in Figs. 4, 105 5 and 6; Figs. 9, 10 and 11 are views, corresponding to Figs. 4, 5 and 6, of a switch adapted for alternating-current work; Fig. 110

12 is a cross sectional view of a detail, taken along the line 12-12 of Fig. 9; Fig. 13 is a view of the laminated bracket of Fig. 9, looking in the direction of the arrow 13, and 5 Fig. 14 is a similar view, looking in the direction of the arrow 14, Fig. 9.

Referring to Figs. 1 and 2, an insulating base or panel 1 carries brackets 2 and 3, supporting a coil 4 which, when energized by 10 current flowing through it, creates a magnetic field for attracting two armatures 5 and 6. A compression spring 7 is mounted upon a non-magnetizable rod 8, and the force exerted by it may be adjusted by means 15 of non-magnetizable nut 8^a. The rod 8 is slidably mounted in projections 9 and 10, which are rigidly connected to, or are integral parts of, the bracket 3. The projections 9 and 10 serve also as pole pieces for 20 the armatures 5 and 6. The upper end of the rod 8 projects through an opening in the armature 6 and is provided with an enlargement or stop 11 for normally engaging this armature. The spring 7 thus normally maintains 25 the armature 6 adjacent to the pole piece 10, but may be separated therefrom by a non-magnetizable bushing or spacer 12 to prevent "freezing".

One end of the armature 5 is provided 30 with ears 13, which are pivotally mounted upon a shaft 14, secured to the bracket 2. A spring 14^a may be mounted upon the shaft 14, as indicated in Figs. 4 and 9, for normally maintaining the armature 5 in contact 35 with the lower end of the rod 8, and an adjustable stop 15 may be provided for limiting its downward movement.

The upper end of the bracket 2 carries 40 a non-magnetizable, U-shaped member 16, in the arm of which is mounted a shaft 17 to serve as a pivotal support for the armature 6. The ends of a spring 18, which is coiled about the rod 17, respectively engage 45 the member 16 and the armature 6 to bias the free end of the armature 6 toward the panel 1. As shown in Fig. 1, an iron screw or other magnetizable member 19 is supported 50 between the arms of the U-shaped member 16 and is longitudinally adjustable to vary the size of the gap 20 between its inner end and the adjacent end 21 of the armature 6. The free end of the armature 6 carries a cross-piece 22 that is preferably loosely mounted at 23 to permit uniform contact 55 between its end 24 and 25 and the stationary contact members 26 and 27 of the relay, the latter members being rigidly secured to the panel 1. The contact members may be employed to close the circuit of the actuating 60 coil of a switch (not illustrated) or may be used for other purposes.

If desired, the gap 20 between the armature 6 and the bracket 2 may be kept constant, in which case a non-magnetizable 65 longitudinally adjustable member, such as

a screw 28 (Fig. 3) may be substituted for the magnetizable member 19, the member 28 being connected to a projection 29 on the armature 6 by a spring 30. By varying the tension of the spring 30, as by 70 means of a nut 31, the same effect may be attained as by varying the gap 20 of Fig. 1. If desired, however, the tension of the spring and the size of the gap may both be varied. 75

The operation is as follows: Upon current flowing through the coil 4, a magnetic field is created which causes the armature 5 to be drawn toward the pole piece 9. The rod 8 is thereupon forced upwardly toward the panel 1 to compress the spring 7 and force 80 the stop 11 away from the armature 6. If the current is above a previously selected safe value, the magnetic field will overcome the force of the spring 18 or the spring 30, as the case may be, and the armature 6 will 85 remain in engagement with the pole piece 10. The ratio of the force exerted by the magnetic field and that exerted by the spring 18 or the spring 30 may be varied, as above described, by adjusting the member 19 or 90 the member 28, as the case may be. When the current falls to the safe value, the spring 18 or the spring 30 will move the armature 6 upwardly with a relatively quick snap movement and thus cause the members 24 95 and 25 to respectively engage the terminals 26 and 27. In the event that the magnetic field becomes too weak to hold the armature 5 in its elevated position, the spring 7, being released, will separate the switch members 24 and 26 and 25 and 27 with a relatively quick snap movement. By utilizing a plurality of relays of this character, the acceleration of the motor may be advantageously 100 accomplished, and the action of each relay, 105 if properly designed, will be delayed until the current traversing the motor circuit has decreased to a safe value.

The function of the spring 7 is obviously to insure that the armature 6 shall occupy 110 its open position at the moment when current is first supplied to the motor and thereafter until the magnetic field created by the current flowing through the coil 4 builds up sufficiently to move the armature 115 5 against the force exerted by the spring. The armature is then maintained in its open position by the force of the magnetic field, although released from the action of the spring. The spring 7 may, of course, be 120 replaced by some other initial holding force. For example, the motor circuits may be so designed as to cause the energization of the coil 4 when the motor controller occupies its "off" position, and at a sufficiently high 125 value to effect movement of the armature 6 in opposition to the force of the spring 18. The spring 7, the rod 8 and the armature 5 may then be omitted, as their functions will be performed by the magnetism of the coil 130

4. Under such conditions, the armature 6 will be moved to, and held in, its open-circuit position by the magnetic field produced by excessive current and will be moved to 5 its closed-circuit position by the actuating spring only when the current falls to a safe value.

For the purposes of motor acceleration, it is necessary to have as many relays as there 10 are main switches. By modifications of structure, however, a single switch may be made to do the work of a large number of relays. I have illustrated such a switch in Figs. 4, 5 and 6.

15 The armature 6 is replaced by any desired number of armatures 6a, 6b and 6c, arranged in any desired way near the coil 4, but all controlled by the single armature 5 through the operation of the spring 7, as 20 heretofore described in connection with Fig. 1. The stop 11 consists, in this case, of a bar engaging all the armatures 6a, 6b and 6c to normally maintain the movable switch members in open-circuit positions. Each

25 armature 6a, 6b and 6c supports a non-magnetizable member 29 to each of which is attached one end of a spring 30, the other end of which is connected to a longitudinally adjustable member 28, as described in connection with Fig. 3. The springs 30 may be adjusted to different tension values, so that the armatures 6a, 6b and 6c, when released by the armature 5, will be successively operated in accordance with 30 successively lower values of the magnetic flux. The members 29 project through their respective armatures to normally engage the pole piece 10 and thus serve as stop members 32 for the armatures. Being made 35 of non-magnetizable material, the stop members serve also the purpose of the bushing 12 of Fig. 1. Adjustable magnetizable members 33 regulate the air gaps 34 between the pole piece 10 and the respective 40 armatures. An additional rod 35 may be fixed to the bar 11 so as to slide through an opening in the pole piece 10 and thereby prevent the bar from turning.

The current in the coil 4 creates a magnetic field which attracts the armature 5, causing it to move from the normal position illustrated in Fig. 4 into engagement with the pole piece 9. The force of the spring 7 is thereupon overcome, and the bar 11 is 50 moved out of engagement with the armature 6a, 6b and 6c, the stop members 32 of which are nevertheless maintained in engagement with the pole piece 10 until the flux of the magnetic field becomes successively sufficiently low to permit the springs 30 to successively actuate the movable switch members of the relays with a relatively quick snap movement, to their closed-circuit positions as described in a co-pending application by H. D. James, control system, Serial

No. 260950, filed Nov. 4, 1918, and assigned to the Westinghouse Electric & Manufacturing Co. The closing of corresponding relays causes the closing of successive switches. In the above-named application, a second 70 coil 36, mentioned below, is illustrated for a purpose therein described.

The armature 5, in addition to performing the function described, may, like the other armatures, control the movements of 75 switch members. I have illustrated one method of effecting this control in connection with the structure illustrated in Figs. 4, 5 and 6, but it will be obvious that the relays of the other figures illustrated in 80 this application may be correspondingly changed, if desired. The armature 5 is provided with an extension 37, preferably of insulating material, which carries a switch member 38 for coöperating with stationary 85 switch members 39, mounted upon the insulating panel 1. The switch member 38 may, of course, be mounted on the body portion of the armature 5.

In Fig. 8, I have diagrammatically shown 90 a system in which the device of Figs. 4, 5 and 6 may be employed. A motor, comprising an armature 40 and a shunt field-magnet winding 41, is connected between line conductors 42 and 43, with an accelerating resistor 44 in series with the armature 40. A portion 4a of the coil 4 is connected across the terminals of the resistor 44. The movable members of switches 45, 46 and 47 are adapted to be actuated by coils 48, 49 and 50 to cause the short-circuiting of successive portions of the resistor 44. The coil 48 is connected in a circuit leading from the line conductor 42 through the switch 51, the armature 6a, and the stationary contact terminal 26 that is adapted to be engaged by the movable contact member 24 of the armature 6a, to the line conductor 43. The coils 49 and 50 are similarly connected to the armatures 6b and 6c, and the other portion 36 of the coil 4 is connected in the circuit of the coil 50. The movable member of line switch 51 is actuated by a coil 52 which is connected in a circuit including contact members 38 and 39. The movable member of a switch 53 is mechanically interlocked with the movable member of the switch 51 to provide a shunt-circuit for a start push-button switch and the contact members 38 and 39. A stop push-button switch is provided for 120 stopping the operation of the motor.

Upon closing the start switch, a circuit is established from the line conductor 42, through the stop and start switches, contact members 39 and 38, and coil 52 to the line 125 conductor 43. The switches 51 and 53 are closed because of the energization of the coil 52. The start button may now be released, the coil 52 remaining energized by the closed circuit extending from the line 130

conductor 42, through the stop push-button switch, the switch 53, and the coil 52 to the line conductor 43. The closing of the switch 51 closes a circuit through the 5 motor extending from the line conductor 42, through the switch 51, the armature 40 and the resistor 44, and the field-magnet winding 41, in multiple, to the line conductor 43. A circuit is also established through the 10 coil 4a in parallel relation to the resistor 44.

The energizing of the portion 4a of the coil 4 creates a magnetic field which attracts the armature 5 to the pole piece 9, which, incidentally, separates the contact members 38 15 and 39. The rod 8 is thereupon actuated, in opposition to the force of the spring 7, to force the bar 11 away from the armatures 6a, 6b and 6c. If the current is above a previously selected safe value, the flux of 20 the magnetic field will overcome the forces of the springs 30, and the armatures 6a, 6b and 6c will remain with the stops 32 in engagement with the pole piece 10 (Fig. 4). As the motor accelerates, and the current begins to die down, the magnetic flux set up by 25 the portion 4a of the coil 4 becomes weakened. After a time, when the flux has decreased to a predetermined value, the spring 30 attached to the armature 6a will overcome the force exerted by the flux of this field, so that the relay controlled by the 30 armature 6a will be closed. The time when this operation will occur will depend upon the size of the air gap 34 and the tension 35 of the spring 30. The armatures 6b and 6c, however, will remain open.

The closing of the first relay establishes a circuit which extends from the line conductor 42, through the line switch 51, the 40 armature 6a, the contact members 24 and 26 of the relay controlled by the armature 6a and the coil 48, to the line conductor 43. The coil 48 becoming energized, the switch 45 becomes closed to short-circuit a portion 45 of the resistor 44. The motor then further accelerates, and, by decreasing the voltage across the terminals of the coil 4, the magnetic field in the neighborhood of this coil is further weakened, which permits the closing 50 of the second relay, controlled by the armature 6b. A circuit is then made from the line conductor 42 through the line switch 51, the armature 6b, the contact members 24 and 26 of the second relay and the 55 coil 49 to the line conductor 43. The coil 49, thus becoming energized, causes the closing of the switch 46 and the consequent shunting of a second portion of the resistor 44. After the motor has accelerated further, 60 the magnetic field surrounding the portion 4a of the coil 4 is again weakened, and the third relay is closed, creating a circuit extending from the line conductor 42, through the switch 51, the armature 6c, the contacts 65 24 and 26 of the relay controlled by the

armature 6c, the coil 50 and the coil 36, to the line conductor 43, thereby causing the energization of the coil 50 and the closing of the switch 47. The whole resistor 44 is then entirely shunted from the armature 70 circuit, and the armature 40 is connected directly across the line.

The shunting of the resistor 44 deenergizes the portion 4a of the coil 4, which would release the armature 5 and cause the 75 relays to be reopened, thus resulting in de-energization of the coils 48, 49 and 50 and the consequent reinsertion of the resistor 44 into the armature circuit, except for the portion 36 of the coil 4, which, as may be 80 seen by the circuit just traced, is energized by line voltage.

It will be noted that the motor circuit was established through the contact members 38 and 39. With these contact members separated, it would be impossible, in the system shown, to start the motor. It is, of course, possible to make the starting of the motor independent of those contact members; but, in the system illustrated, the contact members 38 and 39 serve a useful purpose. If, while the motor is running, the stop button is operated, the circuit of the coil 52, extending from the line conductor 42, through the stop switch, the switch 53, and the coil 50 to the line conductor 43, is opened, and the line switch 51 is, therefore, opened to break the circuit of the motor. The circuit of the portion 36 of the coil 4 and the coil 50, traced above, is also opened at 51; but as the coils are now energized by the counter-electromotive force of the armature 40, the relays and, consequently, the switches 45, 46 and 47, remain closed for a limited time. If the start button were inadvertently 105 or purposely operated during this time, the armature 40 would be thrown directly into the line circuit without any resistance in series with it, were it not that the starting circuit for the motor is open at 38 and 39 110 as long as there is counter-electromotive force enough in the armature 40 to energize the portion 36 of the coil 4 with sufficient force to maintain the armature 5 in contact with the pole piece 9. Not until it has come 115 nearly to rest will it be possible to restart the motor.

In Fig. 8, I have illustrated one system in which my switch may be employed. I make no claim to this system here, as it constitutes 120 the subject matter of a separate application, Serial No. 286,937, filed May 27, 1918, by H. D. James, and assigned to the Westinghouse Electric & Manufacturing Company. Obviously, my switch may also be employed 125 in other relationships. Furthermore, it is not necessary that the contact members 38 and 39 shall be normally closed in the open position of the armature 5, as illustrated in Fig. 4. It is within the scope of my inven- 130

tion to have the contact member 38 close a circuit, as by making contact with the switch 54, Fig. 7, in the closed position of the armature 5.

5 It is possible to modify my invention so as to make it applicable to alternating-current circuits. Such a modified switch is illustrated in Figs. 9 to 14, inclusive. The contact-bearing arm 37, of Fig. 4, has, for 10 clearness, been omitted from the drawings. To reduce eddy currents, the core 55 is slotted, as shown in Fig. 12, and the brackets 2 and 3 are constructed of coarse laminations 56 into which are inserted shading coils 57 15 of conventional type to eliminate chattering, as will be understood by those skilled in the art. If desired, the core 55 may be laminated instead of slotted. As there is no danger of "freezing" in alternating-current 20 systems, where the flux is gradually decreased, there is no need here for the bushing 12 or the non-magnetizable stop 32. The armature members 6a, 6b and 6c are, therefore, held in direct contact with the end 25 58 of the laminated bracket 3, this end 58 serving here as a pole piece. The adjustable gaps 34 of Fig. 4 find their equivalent in adjustable gaps 59 at the rear of the armatures, as in Fig. 1.

30 It will be understood that the structural details of my switch may be varied and modified from what is shown in the drawings and hereinbefore described, and, consequently, that my invention is not limited 35 except in so far as limitations may be imposed by the prior art or are specifically set forth in the appended claims.

I claim as my invention:

1. In a switch mechanism, the combination 40 with a movable member having an operative position and a plurality of springs for respectively actuating said member in opposite directions with relatively quick snap movements, of an electromagnet for assisting 45 one of said springs, and an armature member for rendering said one spring ineffective when said electromagnet is energized above a predetermined degree.

2. In a switch mechanism, the combination 50 with means for creating a magnetic field, and a plurality of armatures controlled by said field, of means for successively actuating said armatures in opposition to said magnetic field, and means for preventing 55 the operation of a plurality of said armatures until one of said armatures has operated.

3. In a switch mechanism, the combination 60 with a movable member having an operative position and a plurality of springs for respectively actuating said member in opposite directions with relatively quick movements, of an electromagnet for assisting one of said springs, and an armature member 65 for rendering said one spring ineffective

when said electromagnet is energized above a predetermined degree, the second spring being rendered effective when the coil is energized below a second and higher predetermined degree. 70

4. In a switch mechanism, the combination with a coil and a plurality of supporting brackets therefor, one of said brackets being provided with a plurality of projections, of a plurality of armatures, one of 75 said projections serving as a pole piece for one of said armatures, and another of said projections serving as a pole piece for said other armatures, switches carried by said other armatures, a spring-pressed rod slidably mounted in said projections to maintain said armatures open, said first armature being adapted to depress said rod in opposition to the force of said spring when said coil is energized, and means for successively closing 80 said switches when the current in said coil falls to predetermined values. 85

5. In a switch mechanism, the combination with a coil, of a slotted core, and a plurality of laminated supporting brackets therefor, 90 shading coils mounted on said brackets, a plurality of armatures adapted to be actuated toward said coil when said coil is energized, and a switch member carried by one of said armatures. 95

6. In a switch mechanism, the combination with means for creating a magnetic field, of a plurality of armatures adapted to be attracted by the force of said magnetic field and retained in their inoperative 100 positions, and means for successively actuating said armatures to their respective operative positions in opposition to the force of said field.

7. The combination with a coil and two 105 spring restrained armatures therefor, of a contact member actuated by one armature, the corresponding spring therefor biasing said contact member to its closed position, means for normally maintaining the contact member in its open position, and adapted to be engaged by the other armature when the coil is energized to permit the other armature to be released when the current traversing the coil falls below a predetermined 110 value. 115

8. In a switch mechanism, the combination with a coil and a main and an auxiliary armature therefor, of a spring actuated means relatively movable with respect to 120 said main armature for normally retaining the main armature in its open position, said means being rendered ineffective to retain said main armature when the auxiliary armature is actuated by said coil, and a spring for actuating the main armature to its closed position when said coil is energized below a predetermined degree. 125

9. In a switch mechanism, the combination with a coil having two pole pieces 130

at one end thereof, and an armature for each pole piece, of a spring depressed member for normally holding one armature in engagement with its pole piece; a spring for actuating said normally closed armature to its open position, and means whereby the other armature so actuates the spring depressed member as to permit the normally closed armature to operate under predetermined conditions in the coil.

10. The combination with a coil and a main and an auxiliary armature responsive to the magnetic flux of said coil, of means relatively movable with respect to said main

armature for normally maintaining the main armature in its attracted position, and a spring for actuating said main armature to its operative position, said auxiliary armature being adapted to actuate said relatively movable means when the coil is energized to permit said spring to actuate the main armature to its operative position when the current traversing the coil falls to a predetermined value.

In testimony whereof, I have hereunto subscribed my name this 29th day of May 1918.

RAY E. DE CAMP.

It is hereby certified that in Letters Patent No. 1,392,249, granted September 27, 1921, upon the application of Ray E. De Camp, of Wilkinsburg, Pennsylvania, for an improvement in "Current-Limit Relays," errors appear in the printed specification requiring correction as follows: Page 3, line 68, for the word "corresponding" read *successive*, and line 69, for the word "successive" read *corresponding*; page 4, line 101, for the article "the", first occurrence, read *these*; and that the said Letters Patent should be read with these corrections therein that the same may conform to the record of the case in the Patent Office.

Signed and sealed this 29th day of November, A. D., 1921.

[SEAL.]

KARL FENNING,

Acting Commissioner of Patents.
